UNITED STATES PATENT OFFICE

M HELEN LANE, OF CHICAGO, ILLINOIS

DESIGN FOR A GAME BOARD

Application filed January 28, 1929. Serial No. 29,797. Term of patent 14 years.

To all whom it may concern:

Be it known that I, M HELEN LANE, a citizen of the United States, residing at Chicago, in the county of Cook and State of Illinois, have invented a new, original, and ornamental Design for a Game Board, of which the following is a specification, reference being had to the accompanying drawing, forming part thereof.

Fig. 1 is a plan view of a game board showing my new design; and
Fig. 2 is an end view of the same.

I claim:

The ornamental design for a game board as shown.

M HELEN LANE.
